CLAIM

I claim the ornamental design for the curved swing lock report cover with opaque backing, as shown and described.

DESCRIPTION

FIG. 1 is a front elevational view of a curved swing lock report cover with opaque backing with the curved swing lock closed showing my new design, the swing lock being shown in broken lines to illustrate environmental features only and forming no part of the claimed design.

FIG. 2 is a top plan view thereof;

FIG. 3 is a bottom plan view thereof;

FIG. 4 is left-side elevational view thereof;

FIG. 5 is a right-side elevational view thereof;

FIG. 6 is a rear elevational view thereof;

FIG. 7 is an elevational view of the inside thereof, shown in an open condition;

FIG. 8 is an elevational view of the outside thereof, shown in an open condition; and,

FIG. 9 is a front elevational view thereof shown with the swing lock open.
